UNITED STATES PATENT OFFICE.

KENNEDY DOUGAN, OF MINNEAPOLIS, MINNESOTA.

TYPE-WRITER.

1,152,494.

Specification of Letters Patent.

Patented Sept. 7, 1915.

Application filed December 27, 1913. Serial No. 808,998.

To all whom it may concern:

Be it known that I, KENNEDY DOUGAN, a citizen of the United States, and resident of Minneapolis, in the county of Hennepin and State of Minnesota, have invented certain new and useful Improvements in Type-Writers, of which the following is a specification.

This invention relates to typewriting machines, and has for its object to provide a small and light machine. This object is attained by a construction which dispenses with keys, key-levers, and type-bars, all of the type being carried by devices mounted upon the fingers of the operator's hands.

In order that the invention may be fully understood, reference will now be made to the accompanying drawings, in which:

Figure 1 is a top view of one form of machine provided with a vertically movable type-guide arranged to actuate the letter spacing escapement, intermediate portions of the carriage and platen being broken out. Fig. 2 is a vertical section of the machine shown by Fig. 1, the section above the base being upon a line *a—a* of Fig. 1, and below the base upon a line *b—b* of Fig. 7. Fig. 3 is a detail view sectioned on line *a—a* of Fig. 1. Fig. 4 is a detail view of a ribbon reel and associated parts. Fig. 5 is a detail view of one of the carriage supporting rollers. Fig. 6 is a detail view of a stop. Fig. 7 Sheet 2 is a top plan view of the carriage tension and escapement elements. Fig. 8 is a detail view of the style of type block seated between guides, which latter are in section. Fig. 9 is a side view of the same form of type block, without said guides, and with a carrying device attached. Fig. 10 is an enlarged section taken on a line *c—c* of Fig. 9. Fig. 11 shows a modification to be described. Fig. 12 shows a style of type carrier like Fig. 9, but having integral studs thereon. Fig. 13 shows a modified connection between a type carrier and its finger attachment. Fig. 14 shows a type carrier having a modified form of guide members thereon. Fig. 15 is a vertical section of the same type carrier in engagement with a coacting guide. Fig. 16 is a top view of a two-hand type guide adapted for the type carrier shown in Fig. 14. Figs. 17 and 18 show two of the three operating

positions of the style shown in Fig. 9. Fig. 19 is a side elevation of a rotary style of type block, said block being turned from its normal position. Fig. 20 is a sectional view on line *s—s* of Fig. 19. Fig. 21 is an elevational view of a modified species of type carrier. Fig. 22 is an end elevation of said type carrier combined with a cross section of a type block guide adapted therefor. Fig. 23 is a top plan view of a type block guide adapted for the type-carrier shown in Figs. 19 and 20. Fig. 24 is an end elevation partly in section of certain parts shown in Fig. 23. Fig. 25 is a front elevation of the type-guide shift-bars and their geared connections with the vertical shaft. Fig. 26 is a side elevation of another style of type carrier, partly in section. Fig. 27 is a top view of the complete device. Fig. 28 is an enlarged detail view of one type block and its spring. Fig. 29 is an end elevation of the parts shown in Fig. 28. Fig. 30 is a top view of a type-block guide, detached. Fig. 31 is a vertical section on line *e—e* of Fig. 30. Fig. 32 is a top view of a rotatable guide, detached. Fig. 33 is a vertical section of said guide and its support, on line *x—x* of Fig. 32. Fig. 34 is a side elevation of said guide. Fig. 35 is a vertical section, on line *y—y* of Fig. 32. Fig. 36 is a bottom plan view of means for turning said guide. Fig. 37 is a side elevation of rack 171, detached. Fig. 38 is a detail view of the mounting of said rack. Fig. 39 is a plan view of a modified turning device. Fig. 40 is a plan view of two interchangeable type block guides, with shifting mechanism. Fig. 41 is a front elevation of same, showing the guides in intermediate positions. Fig. 42 is a detail view of the connections of the cords to the pulley, the pulley being in section. Fig. 43 is an outside view of an operator's glove, before the attachment of type carriers thereto. Fig. 44 illustrates a means of attaching a type carrier to a glove. Fig. 45 is a front elevation of a stall for holding a type carrier, and Fig. 46 is a top plan view of said stall. Fig. 47 is a vertical section on line *v—v* of Fig. 23, omitting the platen. Figs. 48, 49 and 50 are top, side and end views, respectively, of an inking pad by which the inking ribbon 21 may be dispensed with.

Referring to Figs. 1 and 2: 1 is the base of a typewriting machine adapted for the practice of this invention. 2 is a cylindrical platen, having gudgeons rotatably mounted in the end pieces 3 of the carriage 3—4. Preferably, the platen 2 is made hollow. Said carriage has for its base a flat rectangular plate 4 which is longitudinally slidable and is held down to the base and laterally guided by undercut lugs 6 on the base 1 of the machine. Cut in one edge of the carriage base 4 is a rack 7 which engages a pinion 8, which gears with a spur wheel 9, engaged with a spiral spring 10 whose inner end is fixed to a bearing 12. Said spring is tensioned by drawing the carriage to the right, as in ordinary typewriters. The escapement for letter spacing comprises a pinion 13, engaged by rack 7, a star-wheel 14 fixed on the same shaft as pinion 13, and a suitable detent 16 of known construction mounted on a vertically reciprocable rod 17, which is actuated by means presently described. The carriage base 4 is supported by four anti-friction rollers 18, two of which are shown in Fig. 3, said rollers being mounted on fixed shafts 19 held by lugs 20 in the base 1.

The inking ribbon, 21, is preferably carried by and upon the carriage 3—4. Several constructions of this kind are possible. In the construction shown, said ribbon 21 is wound upon a small reel 22 which is detachably mounted on one of the platen-gudgeons 5 between the carriage end part 3 and the platen knob 23. Said knob is quickly detachable to permit removal of the reel 22 and substitution of a fresh reel of ribbon. Said knob is held in place by a suitable spring latch, as 24, the free end of which takes into a small hole in the knob stem 25. Stem 25 and the corresponding hole through the knob 23 are square, so that when the platen is turned by this knob no strain will be placed upon the latch 24. The inner face of the reel 22 bears an annular series of ratchet teeth 26, engaged by a spring pawl 27 which prevents the reel turning in a direction to permit the ribbon 21 to unwind therefrom. Said ribbon is passed between guide-lugs 28 on part 3, thence along and centrally upon the top of the platen, to the opposite end of the platen, to a suitable device for holding the end of the ribbon under tension. The device shown consists of a flat spring 29 mounted on the carriage end 3 and having sharp points 30 adapted to pierce the ribbon. The ribbon is drawn moderately taut and pressed down over said points 30, whereby it will be supported clear of the platen and about $\frac{1}{16}$ inch thereabove. This arrangement of the ribbon reel and spring holder 29 is so simple that it reduces the size and cost of the machine materially and simplifies the construc-

tion. But it will be understood that the invention is not limited to said device nor to its mechanical equivalents.

When the portion of the ribbon that extends across the platen becomes worn out, a fresh length is to be drawn from the reel and the worn portion is to be cut off, the fresh end of the ribbon being then attached to the tension device as aforesaid.

At each side of the printing center 31, a ribbon-supporting device 32 is provided, which permits the ribbon to slide therethrough when the carriage is shifted. As shown, said device comprises a pair of resilient fingers 32, mounted on lugs 33 on a bearing yoke 34. Said fingers 32 extend forwardly and are provided with slotted end portions 35 through which the ribbon is passed.

The type, hereinafter described, are carried by the operator's fingers and are struck down upon the ribbon 21 at the printing center 31, making their imprints upon a sheet of paper passed around the platen from the front of the machine. For drawing in and guiding a sheet of paper Fig. 2 shows a small friction-roller 36 and a curved sheet metal plate 37. Said roller is carried by bearings 38 integral with said plate. Said plate is rockably mounted on a non-rotatable rod 39 by means of lugs 40. The ends of said rod are held by the carriage end parts 3. Roller 36 is held pressed against the platen by torsion springs 41, one end of each of which is secured to a lug 40 on plate 37, the other end being secured to a collar 42 held in position on rod 39 by a set-screw 43.

Means for turning the platen step by step for one, two, and three line spacing, are shown in Fig. 1, but said means are no part of this invention and therefore are not described. There is also shown a simple adjustable carriage-stop 44, for adjusting the width of the margin at the left of the page.

For holding the bottom of a sheet of paper to the platen so that a line may be printed close to said bottom, the drawing shows a pair of fingers 46, both of which are mounted on a rock-shaft 47, journaled in the carriage ends 3. Said fingers are pressed against the platen by a spring 48, acting on a pin 49 projecting from said rock-shaft. By depressing a finger-piece 50 on said rock-shaft, the fingers 46 may be retracted from the platen to permit a sheet of paper to be passed around the platen from below upward, if so desired. Ordinarily a sheet of paper will be first passed under the fingers 46 and back to the roller 36; then a turn of the platen will feed the paper in to the position to receive a date line or a first line of print.

Coming now to the printing means: The forms of printing means which are described first herein, are not necessarily the best

forms in practice, as compared with other forms which are also hereinafter described, but are first described for the reason that they coact with the type-guide shown in Fig. 1.

In Figs. 8, 9, and 10, the type, as the characters will herein be termed, are formed upon one or more sides of a thin, rectangular, preferably square block 54, which may be of any sufficiently hard or tough material. Where three sides of such block are provided with type, the "lower case" characters *h* are placed on the intermediate side as shown; and the capitals, numerals and miscellaneous characters *m* on the adjacent sides. Regarding the number of characters to the side, an odd number is preferable in the present instance, and in order to provide a small and light block it is thought that five characters per side are sufficient. The above described form of type block is to be attached to a finger of the hand, or of a glove, by any suitable device. Portions of such devices are shown in Figs. 13, 17 and 18.

In the structure shown by Figs. 9 and 10, a pair of very thin sheet metal ears 56 are provided with a pair of opposed studs 59 which project both inwardly and outwardly. The inwardly projecting portions 59^a take into a centrally positioned opening in the block 54. The ears 56 are resilient, and exert inward pressure on said block. When removed from the block by being sprung outwardly, they will spring back to their normal relative position.

A slight rocking motion of the type block upon the stud ends 59^a may be provided for by any suitable means. As shown in Figs. 9 and 10, a small pin 57 is fixed in the type block with its ends projecting slightly. To receive said projecting ends a short slot 58 is punched in each of the ears 56. The advantage of this device will be hereinafter stated. Fig. 11 shows another means to the same end. In this device the ears 56 have a slight play between lugs 65, the studs 59 being the pivots of the motion.

The outer stud ends 59 are preferably round in cross-section, and their function is to enable the operator to accurately register the selected type with the printing center 31. As it would be inconvenient for the operator to bring the type carriers into a position at right angles to the longitudinal axis of the platen, there are two type guides provided, and which cross each other at right angles both centering over the same point on the platen. The type carriers on one hand are struck into one of these type carrier guides, and those on the other hand into the other guide.

The type guide shown in Figs. 1 and 2 consists of a sheet metal device having in its upper face two intersecting grooves, R and L, whose intersection is directly above

the printing center 31. Each of said grooves is formed by two pairs of walls 61, whose upper portions are flared apart as shown, and whose lower portions are spaced apart the proper distance to receive and fit loosely 70 a type block 54 or the lower portion of a type block. All the walls 61 are secured to a base plate 62, and some of said walls may be integral with said plate. Intersecting slots registering with grooves R and L are 75 cut through the base plate 62, to permit passage of the type blocks therethrough in any position. Cut in the upper portion of each wall 61 are a series of notches 63 of which there are four pairs for each groove R, L, 80 said notches being adapted to receive the studs 59, guide the type block longitudinally, and permit full depression of such block between the walls 61. Said studs are made of a diameter equal to the thickness of a type 85 block, in order that the walls 61 shall serve as guides for said studs when the middle character of any row of characters is to be printed, for example E in Fig. 8. In other words, the walls 61 themselves will serve 90 the same purpose as if said walls were unbroken by the grooves R, L and had centrally positioned guiding notches for the studs 59. As clearly shown in Fig. 1, the type guide 61-62 has provision for guiding a type block in five positions, regardless of whether the type-block be inserted in its normal position (intermediate side down) or as shown in Fig. 17 or 18. The guiding groove marked R is appropriated 100 to the use of type blocks carried by the right hand, and the cross groove marked L is appropriated to those carried by the left hand. The angles at which said grooves extend are such that the operator's fingers may be 105 held in easy, natural positions while operating, this being of course conducive to speed.

When printing the characters most frequently used, the type block is simply held 110 in the vertical position shown in Fig. 9 and depressed. When printing from the other sides of the type block, the type carrier is to be held as shown in Fig. 17 or Fig. 18 and depressed.

In order that the carriage shall be automatically stepped for each character printed, the type-guide may be mounted for vertical movement, or, the same result may be effected with a stationary guide where other 120 movable elements, arranged to be struck by projections on the type carriers, are provided. The movable guide being thought somewhat the better of the two arrangements, such arrangement is illustrated in 125 Figs. 1 and 2. As shown the base 62 of said guide is provided with a rearwardly extending arm 64, having a pivoted portion 64^a in whose ends are conical holes (not shown) into which project the conical ends 130.

- of set screws 66 which pass through the arms of bearing yoke 34. Integral with portion 64^a is a depending lug 67, which is urged forwardly by a spring 68 secured to a cross-bar 69, Fig. 1. The guide 61—62 is thereby held yieldingly in a position above that to which it is depressed when a character is struck. The downward movement of said guide is adjustably limited by a stop 70, Fig. 10, which is shown as an eccentrically formed lug 70 on a rockable transverse bar 71, whose ends are journaled in the yoke arms 34. Said stop is turned by means of a lever 72, and is fixed in adjusted position by a jam-nut 73 on the threaded portion 74. The upward motion of the guide 61—62 is limited by a stop 76, which is shown as integral with the yoke 34. The escapement connecting rod 17 extends up through a guiding hole in the base 1 and is pivotally connected to the arm 64 by a pin or its equivalent, 77. When the guide 61—62 is fully depressed, arm 64 depresses rod 17 which causes detent 16 to shift, but not to release the star wheel 14. When the guide 61—62 ascends, rod 17 lifts the detent 16 which in so moving permits the star-wheel to be turned one point by spring 10, the star-wheel being then arrested by the detent as is well understood. Said motion of the star-wheel 14 permits rotary motion of pinions 13, and hence a leftward step of the carriage, to position the paper for the next character.
- The forward portion 78 of the guide base 62 may be suitably formed, as shown or otherwise, to provide a spacing key. This key may be struck by the thumb of either hand, without shifting the hand from its usual operating position.
- The guide 61—62 and the members that are integral therewith will be made as light in weight as consistent, in order to reduce the inertia thereof as much as possible.
- In using a plane sided type block, in practice, the block is likely to descend in the guide at an incorrect angle, thereby causing an uneven impression to be made upon the paper. Mechanical means have been devised which will automatically align the type block in this respect, just before the type strikes the paper. A simple form of such means comprises shoulders 79 on each type block, whereby a plain block becomes as shown in Figs. 9 and 10. Said shoulders 79 project slightly from the sides of the block and are parallel and close to the periphery thereof on the three type-bearing sides. For coaction with these shoulders, the inner faces of the guide-walls 61 are formed with narrow seats 80 upon which the shoulders 79 are to be seated, as shown in Fig. 8. Said shoulders are not visible in Fig. 2, as their upper surfaces are in the same plane as the upper surface of the base plate 62. When a type block is pressed down into groove R or L, it

will be automatically aligned by the pressure of the finger upon the carrier, causing the shoulders 79 to seat their full length upon the seats 80 in the guide walls 61. The said grooves R, L being oblique to a line of writing, the type must of course be set obliquely upon the blocks as is shown by Fig. 8.

Before describing any specific finger-attachment devices, the modified forms of type-blocks shown in Figs. 12, 13, 14 and 17 will be briefly described.

The block shown in Fig. 12, is made with the guide-studs 81 integral therewith or tightly fitted in an axial hole therein, instead of said studs being held as in Fig. 10.

Fig. 13 shows a type-block 84 which is made hollow, with stiffening ribs 84^a, and at one side with a heavy portion 84^b into which the stem 85 of a finger clip is screwed.

Figs. 14 and 15 show a type-block 86 provided with a pair of sheet metal side plates 87 secured thereto by rivets 88. Each of said plates is formed with three two-pronged forks, 89, one for each printing face of the block. Fig. 16 is a plan view of a guide which is adapted to coact with this form of type block. This guide is or may be exactly similar to that shown in Fig. 1, with the exception that the spaced tongues 90 between the notches 91 are positioned to guide the forks 89 in adjusting the block for different characters. This is to say; the operator places the forks 89 astride of the proper pair of tongues 90 whereby the type-block is longitudinally adjusted, then depresses the type block as usual, either vertically or in the manner shown by Fig. 17 or 18. Obviously the guide grooves R, L must be unobstructed, in order that they may receive the type-blocks in any position. So, in order to provide substitutes for the tongues 90 that must be omitted on account of this fact, the guide walls 92 are cut away as shown at 93, sufficiently to receive the forks 89 between them when a middle character is to be printed.

The finger attachment device shown in Figs. 17 and 18 and partly in Fig. 9 is made of a single piece of very thin metal, excepting the studs 59. Said piece comprises the aforesaid ears 56, a flat portion 94 connecting said ears, upwardly turned finger clips 96, 97 and two pairs of ears 98 which hold the finger-tip in place. One or both of said clips 96, 97 are provided with suitably positioned ears 99 which aid in holding the device in proper position upon the finger. The clips 96, 97 may engage the sides of the finger, but preferably they engage its front and back, as shown.

In Fig. 13, the finger tip cup 100 is provided with ears 101 to which any desired form of finger clips may be attached.

The type blocks may be rotatably mounted, whereby the type carriers may always be

depressed in one way. A rotatable type block is illustrated in Figs. 19 and 20. The type block 102 is of the same form and has the same arrangement of type as that already described. The studs 103 may be rotatable in the ears 104, and fixed in the block 102, or vice versa. (See Fig. 10). A spring detent 105 is provided for holding the block temporarily at any of the three printing angles. As shown, the detent is integral with one of the resilient sheet metal ears 104. Three indentations 106 are made in the block, to receive the detent in the respective positions of the type block. This type block is to be turned when necessary by pushing any corner thereof against any convenient fixed portion of the machine (see Fig. 1) or against the tabe upon which said machine rests; thereby imparting one or more quarter-turns to the type block, according to circumstances. The characters *h*, of most frequent occurrence, are placed upon the intermediate side of the block.

In Figs. 21 and 22 is shown a form of type-block which is provided with three rows of type but is of smaller dimensions than that heretofore described and is pivotally mounted to turn about an axis that is parallel to the row of type. The type block carrier consists of a sheet-metal yoke 107—108 in whose ends 108 the gudgeons 109 of the type block 110 are journaled. One gudgeon 109 is extended to receive a very small pinion 111. Said pinion is engaged by a segment gear 112 on the end of a lever 113 having opposed lever-arms 114. Said lever is pivoted on a pin 116 and is held yieldingly in a central position by a spring 117. Spring 117 as shown is a leaf spring, and is secured to the cross member 107 of the yoke by a rivet 118. The free end of the spring passes through a slot in the adjacent yoke portion 108 and the extreme end of the spring presses down upon a flat surface of the gear lever 113 between arms 114, holding said lever, pinion 111 and type block 110 at normal position, in which position the type block 110 will stand squarely, with the row of type *h* most often used at the bottom thereof. The yoke ends 108 are provided with guide-lugs 121, 223. In the guide walls 123 are suitable receiving grooves, 122. Said grooves are spaced the distance from center to center of the type in a row, and are upwardly flared, as shown in Fig. 47, to facilitate the insertion of the guiding parts on the type yoke 107—108. The notches 122 are preferably positioned in the four interior corners of the guide 123. These notches 122 receive lugs 121 or 223 on the yoke ends 108 when the type carrier is in extreme position in either groove R, L, and thereby assist in holding the type block in alinement. The guide-walls 123 are set in pairs to form two intersecting grooves, and are spaced at such

a distance apart as to permit the type block to turn upon its axis while between said walls.

In order that the type block shall be caused to turn to present either lateral row of type downward, for printing, two pairs of shift plates 124, 125, 126, 127, are provided, one pair for each pair of guide walls 123. Each of said shift plates is formed with high portions 128 alternating with recesses 129, said high portions being spaced the same as are the guide grooves 122, there being a high portion and a recess for each character in a row on the type block. Each shift plate is mounted movably, whereby either a high 128 or a low 129 may be positioned directly below one of the lever arms on the type carrier. As shown, each shift plate is attached to its guide wall 123 by two screws 130 which pass through a longitudinal slot 131 in the plate, into said wall; said screws are shouldered and permit the shift plates to slide freely the required distance. Normally all four of the shift plates are in inoperative position, that is, their lows 129 are beneath the lever arms 114 in any position of the type block in either groove R or L, said recesses being deep enough to permit a full depression of the type block without actuating either of the lever arms. Any suitable mechanism for shifting the shift-plates when necessary, may be employed. Such mechanism must either shift each plate independently, or one plate of each pair simultaneously. In Figs. 24 and 25 a very simple mechanism is shown by which the last named mode of shifting is effected. A cam ring 132 is rotatably mounted upon grooves in the end walls 133 of the type block guide. Upon the upper face of said ring are four cams 134, 135, 136 and 137. Each cam is in the form of a narrow tongue, having preferably a curvature to reduce friction of operation. Referring to Fig. 22, shift-plate 125 has an extension 138 in the bottom of which is a cam-notch 139 through which the cam 135 is adapted to pass. Each of the other shift plates is identical in construction, and said plates are shiftable in like manner by the other three cams 134, 136, 137, respectively. It is thought the showing in Fig. 23 will suffice for all the parts just mentioned. Fig. 23 shows all four cams in their normal position, in which one end of each is just entered in its notch. If the cam ring 132 be turned clock-wise, cams 134 and 136 will move shift-plates 124 and 126 inwardly, while the other two cams 135 and 137 will recede from their shift-plates without moving them. By turning the cam ring back to normal, shift-plates 124 and 126 are replaced in normal position. If the cam ring be turned counter-clockwise from normal position, cams 135 and 137 will move shift-plates 125 and 127 inwardly, while the

other two shift plates will be unaffected. The reverse movement of the cam ring will restore the shift plates 125 and 127 to normal. The cam ring is provided with an arc gear 140, which meshes with a pinion 142 on a vertical shaft 143. The upper bearing of shaft 143 is provided by an opening in a plate 144 which is rigidly secured to the front type-guide walls by screws 146. The type-block guide 123—133 is to be mounted like that shown in Fig. 1, and the plate 144 provides a spacer-key, corresponding to the part 78 shown in Fig. 1. Pinion shaft 143 is journaled in the base 146 and has keyed thereon an arm 147 to which is connected a tension spring 148 which normally holds the pinion 142, cam ring 132, cams, and shift plates, in normal positions. For turning the shaft 143, any suitable means may be provided. As shown in Figs. 24 and 25 there is a shift-bar, 149—149, extending right and left from the shaft 143. Said shift-bar is pivoted in bearings 150 and acts on shaft 143 through bevel gears 151, 152, 153, 154. Depressing the front side of either half of the shift-bar will turn the parts in one direction, and depressing the rear side of said shift-bar will turn the parts in the opposite direction. The parts referred to will be automatically returned to normal by the spring 148. The pinion 142 is sufficiently lengthened below the gear 140 to retain its engagement with said gear when the type block guide is depressed by the operator for the purpose hereinbefore stated.

When a normal character is to be printed, the operator inserts the guide lugs 121 in the proper pair of grooves 122 and depresses the type-carrier until the type strikes the paper through the ribbon 156. Both of the lever-arms 114, will pass down into recesses 129 and will not be turned, hence the type block 110 will not be turned. Now suppose that the next character to be printed lies on a lateral side of a type block on the operator's right hand, and that the type block must be turned to the right in order to print said character. With the left thumb 40 the operator actuates shift bar 149 in the proper direction, and inserts the type block in the groove R in the correct longitudinal position. Said movement of the shift bar 149 causes cam 134 to shift plate 124 inwardly, whereby the highs 128 of said plate will be placed in the positions normally occupied by the lows 129. Now when the type carrier is depressed, the left hand lever-arm 114 (seen as at the right in Fig. 22) will be forced upwardly by one of said highs 128, whereby the pinion 111 and type-block 110 will be turned to the right, the latter receiving just a quarter-turn before its rotary motion is stopped by a lug 156 on gear 112, 45 striking the pinion 111. During this stroke

the operator keeps his left thumb on the shift-bar 149, but as soon as the character is printed he removes the pressure from the shift-bar, permitting the spring 148 to return the shift-plate 124 to normal by the mechanism described. In the case just described, one shift-plate 126 of the unused groove L was actuated, but that motion had no effect, and the simultaneous actuation of two shift-plates permits of a simpler mechanism for operating the shift-plates. 50

The operation of the shift-plate having been fully described for one character, its use for any character will now be readily understood. 55

The form of type carrier and type block guide, shown in Figs. 21 and 22, may of course be embodied in a machine like the machine shown in Figs. 1 and 2.

Certain modified printing means are shown in Figs. 26 to 29, inclusive, and will now be briefly described. 60

Figs. 26 and 27 are a sectional side view and a top view of a one-finger type carrier in which a plurality of type blocks are carried. The remaining figures illustrate various forms of type block guides and selecting devices with which a machine must be provided in order to utilize these forms of type carriers. In Fig. 26 and Fig. 27, the finger clip 155 is one piece of sheet metal: Rigidly mounted thereon are six pairs of jaws 157, and pivoted in each pair of jaws is a type-block 158. Each type block bears two type 159, one on each end. These type blocks are free to turn 90 degrees in either direction, but normally each block is held in a transverse intermediate position (as shown) by a spring. One form of spring for the purpose is shown at 160, Fig. 28. 65 This is a tension spring, and pulls on a pin 161 on the type block 158. The simplest form of guide for these type blocks is illustrated in Figs. 30 and 31. This guide consists of a square tube 162 having four upwardly flaring walls 163. In the bottom of the guide is a reduced square opening 164. The diameter of the larger passage 165 equals the width of the jaws 157, while the diameter of the reduced opening 164 equals that of the type block 158 itself. In selecting the character to be printed, the operator strikes the end of the type block that is to be turned up, against one of the flaring walls 163, and pushes down, thereby lowering the proper end of the type block into the passage 165, through the guide opening 164, onto the receiving surface (ribbon or paper). Upon removal of the carrier the type block is returned to normal by its spring 160. This guide 162—163 will answer for the type blocks carried by both hands, as will be readily understood by reference to Fig. 30. 70

The selection of which side of the guide

to be struck, may be obviated by providing a guide that is capable of rotary movement. Such a guide is illustrated in Figs. 32 to 38 inclusive. In this guide the walls 166 are only slightly flared. In two adjacent walls are cut two recesses *r*, *l*, which permit one end of a type block to descend therein, the other end being upheld by one of the walls 166. (Fig. 33). Types carried by the right hand are depressed through recess *r*, and type carried by the left hand are depressed through recess *l*, the recesses being either turned toward the operator, or turned 180 degrees therefrom. When said recesses are pointed toward the operator, that end of a type block nearest the operator will be depressed, but should the guide be turned 180 degrees, the opposite end of the type block would be depressed, and a different character be printed. On the guide piece 166 are an annular flange 167 and a ring of pinion teeth 168. A plate 169 (Fig. 36) has a circular opening which loosely fits in the annular groove 170 and supports the guide. A rack 171 is mounted slidably on plate 169 and engages the pinion teeth 168. Said rack is capable of turning the guide 180 degrees, and is provided with finger-pieces 172, 173, by which it may easily be actuated. A stop 174 on the rack limits its travel in one direction by striking a stop 176 on the bottom of plate 169. One finger piece 173 limits the opposite travel by striking the side of plate 169. The rack is supported by a piece 177 (Fig. 38) through which screws 178 pass into a piece 179 on the upper side of said plate. The rack 171 is manipulated according to the positions of the types that are used, some types requiring a turn of the guide 166 and others not requiring such movement.

Fig. 39 shows a curved gear 180 for turning the type block guide. Said gear is actuated by manipulating the finger-piece 181. An equivalent effect may be obtained by employing duplicate type block guides, with means for moving either one of them to the printing position. As shown by Figs. 40 and 41, two type block guides 186, 187 are rigidly mounted on an angle-lever 188 which is fixedly mounted on a vertical rock-shaft 189 having bearings 190 on a post 191. In one of said guides the recesses *r* and *l* face the operator, but when the other guide 187 is brought into position for use its recesses *r* and *l* are oppositely disposed. Fixedly mounted on the shaft 189 is a grooved pulley 192, to the periphery of which the ends of two cords 193, 194 are fastened, cord 193 being fastened to a pin 196, and cord 194 to a pin 197. Said cords are partly wound upon the pulley and in the same direction, and the winding is performed by a torsion spring 198 which also holds the angle-lever 188 in the position

shown, against a stop 199, in which position of the lever the guide 186 is in operative relation to the platen, 200. To cause an opposite character to be printed, the operator pulls on either cord 193, 194, thereby turning the lever 188 until it abuts another stop 201, and holds the cord in order to hold the guide 187 in operative position. As soon as the character has been printed the cord is released, and the spring 198 restores the other guide to operative position. By arranging the more frequently used characters to be operated in the normally positioned guide 186, the number of shifts from this guide to the other may be reduced to a minimum.

Instead of mounting the type carriers directly upon the fingers, the *type* carriers may be permanently attached to gloves, one of which is shown by Fig. 43, the back of the glove being shown. This is what would be termed a skeleton glove, as unnecessary portions thereof are cut away in order that the hand may be cooler and its fingers have freer play. The knuckle band 203 is connected with the wristband 204 by two or more narrow strips 206. The ends of the fingers are cut away on the back, as shown at 207. The inner sides of the glove fingers 208, are left full length or nearly so, forming tags 209 and the type carriers are fastened to said tags in any suitable manner. One device for this purpose is represented by Fig. 44, in which a type carrier of any kind is indicated. A slot 210 is punched through the clip 211 that engages the inner side of the finger. The tag 209 of the glove is looped through said slot 210 and sewed together at 212, thereby neatly fastening the type carrier to the glove. Any of the type carriers herein shown may be attached by this device.

Figs. 45 and 46 illustrate a stall for holding a type-carrier when the latter is not in use and also to facilitate the placing of the type carriers upon the fingers. Of course there will be as many of these stalls as there are type carriers, but the illustration of one will suffice for all.

Fig. 45 is an elevation, facing the operator, and Fig. 46 is a top view, in which the position of a type carrier like that shown in Fig. 22 is indicated by dotted lines, 110 being the type block, 114 the lever-arms. A pair of opposed springs 213 have a common base 214 which is secured to any horizontal surface by screws 215. Springs 213 converge rearwardly and at their free ends are bent outwardly, forming inclined shoulders 221. The height of springs 213 is about that of the guide lugs 121 (Fig. 22) which lugs the shoulders 221 are adapted to engage. Adjacent the free end of each spring 213 is an upright spring 216, having a foot 217, secured to the surface above mentioned,

by screws 218. Each spring 216 is formed with an inwardly facing shoulder 219, and with a lip 220 extending upwardly from said shoulder. Said shoulders are so spaced as 5 to receive between them and hold down the lever arms 114 when the type carrier is fully depressed. One of the springs 216 is provided with a lug 222.

The operation will be as follows: the type 10 carriers, being in their stalls, are placed on the fingers by inserting the fingers downward into them. The type carriers are removed from the stalls by pulling the fingers toward the operator. The type carriers are 15 removed from the fingers by inserting them downward into the stalls and pulling the fingers up out of them.

Figs. 48, 49 and 50 are top, side and end views, respectively, of an inking pad by the 20 use of which the inking ribbon 21 may be dispensed with. The pad, 224, is mounted on a metal base 225, in the rear margin of which is a longitudinal undercut groove 226. 25 227 are two type block turning members, one for each hand. These members extend across the pad and are sufficiently high to engage and actuate the lever arms 114 of the species of type block shown in Fig. 22. Each member 227, is provided with a foot 30 228 which slidably fits in the groove 226. A thumb-screw 229 is threaded through the foot 228, and by pressing upon the bottom of the groove, binds the member 227 any desired point along said groove.

35 To ink the type of a type block of the species shown in Figs. 9, 11, 12, or 19, it is only necessary to press the side to be inked, upon the pad 224. To ink the type of a type block of the kind shown in Fig. 22, the 40 lateral type rows are inked as follows: to ink the right hand lateral row of type, the type block is placed at the right of one of the members 227, and the lever arm 114 adjacent said member is pressed down upon said member, by depressing the finger clip 115. Thus the type block 110 will be turned 45 in the proper direction to bring the desired row of type down upon the pad. To ink the other lateral row of type, the type block is placed at the other side of the member 227 and the other lever arm 114 pressed down thereagainst. The forward portions of the members 227 serve as guides for holding the type carriers from turning on the fingers 50 during the inking operation. The members 227 are made slidable so that they may be moved to a fresh portion of the pad when the ink becomes scant on the portions of the pad adjacent them. This pad may be 55 mounted upon the base of a typewriting machine, if so desired.

Having described my invention, I claim, and desire to secure by Letters Patent:

60 1. In combination, a multicharacter printing device adapted to be carried by a finger

of the hand, a device for holding a sheet of paper to receive the printing, and a guide adjacent to the paper holding device, said guide being adapted to guide said printing device.

70

2. In combination, a multicharacter printing device adapted to be carried by a finger of the hand, a carriage for holding a sheet of paper to receive the printing, and a relatively fixed guide for guiding the printing 75 device.

80

3. In combination, a multicharacter printing device adapted to be carried by a finger of the hand, a guide for guiding said printing device, and character selecting means on said printing device and guide.

85

4. In combination, a multicharacter printing device comprising a finger clip and a type block carried by said clip, means for holding a sheet of paper to receive the printing, a guide for guiding said printing device, and character selecting means on said printing device and guide.

90

5. In combination, a type carrier comprising a finger clip and a multicharacter type block; means for holding a sheet of paper to receive the printing, and a guide for guiding said type block.

95

6. In combination, a frame, a paper holding device and a type block guide both mounted on said frame, and a type carrier comprising a part adapted to be carried by a finger of the hand and a multicharacter type block adapted to be passed through said 100 guide in its printing stroke.

100

7. In combination, printing devices adapted to be carried by the fingers of each hand, means for holding a sheet of paper to receive the print, and a guide adapted to receive and guide the printing devices carried 105 by either hand.

105

8. In combination, printing devices adapted to be carried by the fingers of each hand, means for holding a sheet of paper to receive the print, and a guide having two grooves 110 therein, said grooves being adapted to receive and guide the printing devices carried by the right and the left hand, respectively.

110

9. In combination, a carriage comprising a platen and paper holding means, a vertically movable type block guide, means actuated from said guide for stepping the carriage longitudinally, and a printing device comprising a finger clip and a type block 115 carried by said clip.

115

10. In combination, a carriage comprising a platen and paper holding means, an escapement for the carriage, a movable type block guide, means actuated from said guide for operating the escapement, and a printing device comprising a finger clip and a type block carried by said clip; said guide being actuated by the printing motion of 120 said type block.

120

11. A typewriting machine comprising a 130

longitudinally movable carriage, an escapement for the carriage, a platen in the carriage, an ink-ribbon, a movable type-block guide positioned close to the platen, type-carriers adapted to be carried by the fingers of the hands, each of said type-carriers comprising a type block adapted to be passed through said guide upon said ribbon in its printing stroke, and an operative connection between said guide and said escapement, said guide being actuated by the printing motion of said type blocks.

12. A typewriting machine comprising a longitudinally movable carriage, an escapement for the carriage, a platen in the carriage, an ink-ribbon, a movable type-block guide positioned close to the platen, type-carriers adapted to be carried by the fingers of the hands, each of said type carriers com-

prising a type-block adapted to be passed 20 through said guide upon said ribbon in its printing stroke, and an operative connection between said guide and said escapement, and a spacing key carried by or upon said guide.

13. In a typewriting machine, a carriage, 25 a ribbon magazine and a ribbon tension device each mounted upon the carriage, a platen in the carriage, a type block guide positioned close to the platen, an ink-ribbon extending from said magazine, between said 30 guide and the platen, to said tension device, an escapement for the carriage, and means actuated by manual movement of said guide for operating the escapement.
